INVENTOR.

J. W. Davidson

BY ATTORNEY.

UNITED STATES PATENT OFFICE.

JEFFERSON W. DAVIDSON, OF DENVER, COLORADO.

WATER-TIGHT JOINT AND METHOD FOR ITS PRODUCTION.

Application filed April 24, 1923. Serial No. 634,286.

My invention relates to water-tight joints and a method for their production, and its principal object is to provide a simple, durable and very effective means to prevent 5 leakage of water between the base of a water closet, washstand or other similar fixture, and the floor or other surface upon which it is supported, or around a pipe or other water conduit where it passes through the 10 floor.

Another object of the invention is to provide a water-tight joint around a fixture or conduit of the nature above referred to, which will effectively prevent water from 15 seeping underneath a carpet, linoleum or other floor covering, through the space between the edge of the covering and the part of the fixture or conduit at which it adjoins the floor upon which the covering is laid.

20 An embodiment of the invention has been illustrated in the accompanying drawings in the various views of which like parts are similarly designated and in which—

Figure 1 is a sectional plan view of the 25 basal portion of a water closet to which my invention is applied;

Figure 2, a section taken on the line 2—2, Figure 1;

Figure 3, an enlarged sectional view of 30 the water-tight joint and the parts to which it is applied; and

Figure 4, a perspective view of a piece of the rubber molding strip which is an essential element of the joint.

35 Referring to the drawings, 5 designates the base of a water closet supported on a floor 6 which has a covering 7 of carpet, linoleum or other suitable substance.

40 An opening 8 in the base connects with a soil pipe 9 which extends through a hole in the floor.

In order to produce a water-tight joint around the base in accordance with my invention and thereby prevent spilled water 45 from leaking either beneath the base or underneath the floor covering, I cover the joint between the edge of the base and the floor covering by a gasket 10 of putty or other similar plastic filler, and cover the gasket and the surrounding portion of the floor 50 with a coating 12 of white lead or other pigment. I then place a strip 13 of rubber molding snugly around the coated filler to form a continuous band and fasten the

strip in place by nails or brads 14 driven 55 into the floor. The joint thus produced may be covered with enamel or other paint to fill possible cracks or apertures and to give to the joint a finished appearance in harmony with the parts to which it is applied. 60

The rubber strip 13 which is an essential element of the joint, is preferably rounded at its upper side to provide a curved surface between the base and the floor covering; its lower side is flat to evenly engage the floor 65 covering or other surface upon which it is fastened, and its inner side or edge is beveled inwardly to provide a space for the filler which preferably is made of triangular section with its outer side sloping from 70 the edge of the base to the surface of the floor covering.

It will be evident that the joint thus produced covers the space between the edge 75 of the floor covering and the base and thoroughly closes it against the passage of water, and it is to be understood that the joint may be formed in like manner around water conduits where they adjoin or pass through an opening in a floor or other surface or around the base of a washstand or other fixture, and that while it is particularly adapted to cover the space between a floor covering and a fixture, it is also of value if applied directly to the surface of 80 a floor where no covering is provided.

Variations in the materials used in the production of the joint and in the form and arrangement of the constituent elements of the same may be resorted to within the spirit 90 of my invention as defined in the following claims.

What I claim and desire to secure by Letters Patent is:

1. A joint of the character described comprising in combination with the foot of a water fixture, having a surface extending upwardly from the floor, a floor covering terminating adjacent said surface, in slightly spaced relation thereto, a plastic filler 95 covering the space between the covering and the foot of the fixture in engagement with said surface of the foot, and a flexible packing strip secured to the floor upon said covering and bearing at its upper edge 100 against the foot of the fixture above the plastic filler, the inner face of the strip opposite said surface being inclined away from 105

the surface from its said upper edge downwardly to compress the filler between the strip and the foot.

2. A joint of the character described comprising in combination with the foot of a water fixture and a surface upon which it is supported, a strip nailed upon the surface around the foot of the fixture, the

inner face of the strip being inclined from its upper edge which engages the foot of the fixture, away from the same to provide a recess of a wedge-shaped cross section and a plastic filler in the recess.

In testimony whereof I have affixed my signature.

JEFFERSON W. DAVIDSON.
